APPARATUS FOR AUTOMATICALLY GLAZING ELEMENTS ARRANGED ON FLEXIBLE BANDS, PARTICULARLY FOR COLORING SLIDING CLASP FASTENERS

Ettore Armari, Chiasso, Switzerland

Application March 14, 1950, Serial No. 149,608
In Switzerland March 14, 1949

13 Claims. (Cl. 118-2)

1

The present invention relates to an apparatus for automatically coating articles or elements and more particularly to the coloring of elements arranged on or embodied with flexible bands.

The invention particularly relates to the coloring of sliding clasp fasteners and has particular but not exclusive reference to fasteners commonly known as rapid fasteners which incorporate metallic elements that are to be colored to correspond with the color of a textile band on which the fasteners are mounted.

In general this type of color operation has been previously performed by spraying coloring matter through manual control and operation and thus necessitates employment of suitable protecting or masking means to shield or protect the supporting textile band.

Obviously, manual control and operation is laborious and the result obtained does not always satisfy the particular requirements.

Accordingly, the present invention has for an object to provide coloring apparatus which is automatically controlled responsive to the presence or absence of articles to be colored in a particular zone of the apparatus adjacent a spray gun or nozzle.

Accordingly the invention includes a conveying and guiding means for at least one flexible band on which the articles to be colored are carried and includes further a stationary masking or protecting means provided with at least one opening of a predetermined width and through which project at least a part of the surface of each article or object to be colored. The apparatus further includes at least one spray nozzle adapted to project coloring matter on to the object to be colored during the time interval that the articles pass by and project through the opening or openings provided in the masking means.

The apparatus likewise includes in combination with the spray nozzle or nozzles, means adapted to automatically control the operation thereof in dependence upon the presence or absence in the space between the edges defining the opening in the masking means, of the objects to be colored.

The attached drawing illustrates by way of example, an embodiment of the apparatus according to the invention, in which:

Figure 1 is a longitudinal sectional view of the apparatus.

Figures 2 and 3 are sections on an enlarged scale on lines II-II and III-III of Fig. 1.

Figure 4 is a partial front elevation of the

2

masking means with the spray nozzle removed.

The apparatus illustrated includes a conveying drum 10 keyed on a shaft 12, suitably carried in supports provided in a frame of the apparatus, not shown. On one end of the shaft 12 is keyed a pulley 14 rotated by a belt or other suitable transmission means driven by a motor 15.

Drum 10 is provided, on the middle of its peripheral surface with a groove 16, so dimensioned that it may receive the elements B which are to be colored and which are embodied with or carried by the flexible band C. As shown, the groove 16 is of less depth than the thickness of the elements B so that the latter project above the adjacent peripheral surface of the drum on opposite sides of the groove.

The drum 10 has at its edges two rims 18 which, together with the middle groove 16, form a part of the guide member. The peripheral surface of drum 10 is suitably provided with teeth or milled; for the purpose of exerting an engaging action on the flexible band C.

Along a part of the peripheral surface of drum 10 are disposed curved metallic strips 20, which are arranged in front of the peripherally milled surface of the drum 10 and are so arranged as to form together, with said surface a pair of effective guide surfaces which preferably extend from the upper part of the drum to and terminate after having extended through an arc greater than 90 degrees.

The metallic strips 20 have at their upper ends curved elements 22 adapted to facilitate, in the manner hereinafter described, the insertion of the flexible band, supporting the objects to be colored. Said curved elements 22 are combined with a plate 24 on which is placed the flexible band to be inserted in the curved channel or opening formed between the strips 20 and the periphery of the drum 10.

Pairs of rollers 26 cause the metallic strips 20 and the flexible band C to adhere to the periphery of drum 10 and guide this latter when it is discharged at the lower part of the above curved channel. The adherence of these bands may also be effected in another manner, as for instance, by means of springs suitably applied and pressing against the metallic strips.

A cover or shield 28 is arranged in correspondence with the horizontal diameter of drum 10 and is provided in its bottom 30, see Fig. 4, with an opening or split 32 of substantial size, that is the opening extending a substantial distance above and below the axis of the nozzle and through which opening project a part of the metallic ele-

55

ments B to be colored as the flexible band C moved past the opening 32. The bottom 30 is curved so as to register with the outer part of the strips 20 on which the cover or shield 28 is fixed, or when these latter strips are of limited length the curved bottom forms a continuation of said strips.

In front of the cover 28 is placed the nozzle 34 of a spray means 35 for the coloring substance, said spray means being connected in a known manner with a compressed air source. The valve member 36 controlling said nozzle is connected, through suitable linkages, with a lever 38, which in its turn, is connected with the armature of an electromagnet 40, the energization of which is controlled by contacts 42 suitably protected and controlled by a double-arm lever 44, one arm 45 of which is suitably profiled and is arranged in correspondence to the groove 16 of the drum 10.

This arm 45 is disposed in a suitable angular position, with respect to the drum 10, so as to together with the contacts 42 constitute, in effect, actuating means to control the electromagnet 40 in due manner as will be set forth hereinafter. The cover 28 has an upper opening with which communicates a suction pipe 45' and at its lower side a tank 29 for collecting the varnish.

The apparatus is completed by a scraping member 46 placed in correspondence to the lower part of the drum 10 and which scraping member or blade removes from the groove 16 the coloring material deposited therein.

In correspondence to the lower part of the drum a reel 48 is arranged on which is wound the flexible band carrying the colored elements, so that the drying of the same can be effected.

The winding of said band on the reel 48 is helically effected in order to avoid overlapping which would have deleterious effects on the freshly colored elements. It is obvious that the reel may be omitted when short pieces are colored, or when the apparatus is provided with drying means, such as infra-red ray lamps past which the band and colored elements pass to be dried.

It is believed evident that when a band provided with the elements to be colored or glazed is placed on the plate 24 and moved therealong so that the lead end of the band is engaged by the milled surface of the drum between the latter and the curved guide plate 20, then the rotation of the drum feeds or moves the band. The metallic elements B to be colored are disposed with their lower part in the groove 16 and with their upper part projecting into the split or opening formed by the facing strips 20. When the first of said elements arrives in correspondence to the position of arm 45 of lever 44, it contacts and moves said lever which movement closes the contact device 42 and energises the electromagnet 40. This latter opens the valve member 36 thus effecting spraying of coloring material with the spraying continuing as long as the contacts of the contact device 42 are closed. When the succession of the metallic elements B to be glazed have device, the contact 42 opens and the valve member 36 is thus closed. As it is easy to understand the positioning of the arm 45 of lever 44 is provided, in practice, in such a manner, that when controlling the valve member 36, the first of elements B of the group to be colored lies closely superjacent the upper periphery of nozzle 34, whilst, when closing the valve member, the last of said group of elements lies closely subjacent the lower periphery of said nozzles 34.

In such a manner it is possible to continuously

and automatically color the elements B, depending upon the presence or absence of the elements B in front of the spray nozzle 34.

The rotational speed of the drum 10 may be 5 suitably varied through interposition of a change speed gear between the motor 15 and the belt transmission to the drum, in dependence upon work performed. Also the opening or split 32 may be of variable width in dependence upon the 10 dimensions of the elements B to be colored. The width between the two curved metallic strips 20 may be also varied.

Although there has been described and shown a particular form of an apparatus for coloring the metallic elements of sliding clasp fasteners, said apparatus may serve also for a continuous coloring of any object placed on or carried by bands.

What I claim is:

20 1. Apparatus for automatically coating articles particularly for coloring slide fasteners arranged substantially in the longitudinal central zone of flexible bands, comprising in combination, a rotatable drum, means for controllably rotating the same, said drum having at least one peripheral groove therein for accommodating a flexible band having slide fasteners associated therewith, masking means combined with a portion of the periphery of said drum 25 and including means defining an opening of predetermined dimensions past which opening said band and fasteners pass, spraying means combined with said masking means and including at least one controllable spray nozzle directed toward said opening and through which coloring material is projected, and electro-mechanical means operatively associated with the nozzle and including actuating means disposed adjacent said opening and operable responsive to the passage of said band for controlling the nozzles and thereby the passage of material through said nozzle so that said controllable nozzle is operative upon actuation of said electro-mechanical means to spray material when said band and the fasteners thereon are passing before said opening and inoperative when said band and fasteners are not passing in front of said opening.

40 2. Apparatus as defined in and by claim 1 in which said electro-mechanical means includes actuating means comprising a double-arm lever, an electric contact device controlled by one arm of said lever, the other arm of the lever being disposed to cooperate with the fasteners passing by said opening, and an electromagnet controlled by the contact device including an armature, a valve for said spray nozzle and mechanical means connecting said armature with said valve so that movement of the armature responsive to closing or opening of the contact device effects closing or opening of the valve.

45 3. Apparatus for automatically coating articles particularly for coloring slide fasteners arranged substantially in the longitudinal central zone of flexible bands, comprising in combination, a drum rotatable about a horizontal axis, said drum having at least one peripheral groove therein of a depth less than the thickness of the articles to be colored and said groove receiving the articles with the band contacting the peripheral surface of the drum adjacent the groove and a portion of each article projecting above the said adjacent peripheral surface, spaced curved strips mounted in spaced

relation with respect to and conforming to the periphery of the drum with the spacing between the strips substantially conforming to the width of the groove and the space between the strips and the periphery of the drum defining a curved channel through which passes the flexible band carrying the articles, said articles having dimensions such as to project above the upper face of the strips, a spray nozzle directed toward the periphery of the drum, shielding means including a plate member having an opening therein registering with the space defined by the said strips and extending a substantial distance above and below the axis of the nozzle, said plate member being disposed between the drum and the spray nozzle and overlying and shielding the band on the opposite sides of the articles, a substantially horizontal plate mounted in juxtaposition of the upper peripheral surface of the drum at the upper end of said curved channel defined between the drum periphery and the curved strips for receiving the band in feeding position relative to the upper part of the drum, and electro-mechanical means for controlling said nozzle and including actuating means disposed adjacent said opening and operable responsive to the passage of said band and the articles thereon past said opening for controlling said spray nozzle so that the latter is operative to spray material upon the actuation of said electro-mechanical means when the first article on the band has moved to a position superjacent the axis of the nozzle and at said opening and inoperative to spray material when the last article on the band has moved past the same position.

4. Apparatus as defined in and by claim 3 including spaced rims provided on the peripheral surface of the drum and constituting guide members for the edges of the flexible band.

5. Apparatus as defined in and by claim 4 in which a pair of rollers are mounted at accurately spaced positions for urging the flexible band against the peripheral surface of the drum.

6. Apparatus as defined in and by claim 5 in which at least a portion of the peripheral surface of the drum is roughened to facilitate feeding action of the band.

5 7. Apparatus as defined in and by claim 6 in which scraping means are provided adjacent the lower part of the drum to remove the excess coloring material deposited thereon.

8. Apparatus as defined in and by claim 7 and 10 a collecting reel mounted adjacent the drum for receiving the band with the articles thereon.

9. Apparatus as defined in and by claim 8 in which the said reel is so disposed and rotated that the band is helically wound thereon.

15 10. Apparatus as defined in and by claim 3 and drying means mounted adjacent the lower part of the drum through which pass the band and the articles to be dried.

11. Apparatus as defined in and by claim 10 20 in which the drying means comprises infra-red ray lamps.

12. Apparatus as defined in and by claim 3 in which a shielding cover is incorporated with said plate and a suction pipe communicating with said cover.

25 13. Apparatus as defined in and by claim 12 in which the said plate constitutes the bottom of said cover.
